UNITED STATES PATENT OFFICE

143,710

DESIGN FOR A HOUSEHOLD COMBINATION TOOL

Douglas T. Burch, Redwood City, Calif.

Application August 20, 1945, Serial No. 121,521

Term of patent 7 years

(Cl. D44—29)

To all whom it may concern:

Be it known that I, Douglas T. Burch, a citizen of the United States, residing at Redwood City, county of San Mateo, State of California, have invented a new, original, and ornamental Design for a Household Combination Tool, of which the following is a specification, reference being had to the accompanying drawing forming a part thereof.

In the drawing:

Fig. 1 is a side view of the household combination tool showing my new and ornamental design.

Fig. 2 is a similar view of the opposite side of the tool.

Fig. 3 is a left end view of the tool of Fig. 1.

Fig. 4 is a right end view of the tool of Fig. 1; and

Fig. 5 is a fragmentary sectional view taken on the section 5—5 of Fig. 2.

I claim:

The ornamental design for a household combination tool, substantially as shown.

DOUGLAS T. BURCH.
